UNITED STATES PATENT OFFICE.

JOHN DUDEK, OF CAMPBELL, NEBRASKA.

ROAD-DRAG.

1,239,366.

Specification of Letters Patent.

Patented Sept. 4, 1917.

Application filed February 16, 1917. Serial No. 149,068.

To all whom it may concern:

Be it known that I, JOHN DUDEK, a citizen of the United States, residing at Campbell, in the county of Franklin and State of 5 Nebraska, have invented new and useful Improvements in Road-Drags, of which the following is a specification.

This invention relates to road working machines and it has particular reference to 10 that class of devices which are known as drags or levelers.

The invention has for its object to produce a road drag of simple and improved construction which will be equipped with a 15 blade or cutting member located well in advance of the forward runner or drag bar, the purpose of said cutting member being to shave or cut uneven or irregular portions of the road in advance of the drag, 20 the dirt thus cut being deposited in advance of the drag to be thereby crushed, leveled and compacted, filling the low spaces and leaving a smooth and perfect surface for traveling.

25 A further object of the invention is to so mount and support the blade or cutting member that it may be tilted in an upward direction when necessary to enable it to pass over obstructions. A further object of the 30 invention is to simplify and improve the construction as well as the manner of supporting the improved blade or cutting member.

With these and other ends in view which 35 will readily appear as the nature of the invention is better understood, the same consists in the improved construction and novel arrangement and combination of parts which will be hereinafter fully described 40 and particularly pointed out in the claims.

In the accompanying drawing has been 45 illustrated a simple and preferred form of the invention, it being, however, understood that no limitation is necessarily made to the precise structural details therein exhibited, but that changes, alterations and modifications within the scope of the claims may be resorted to when desired.

50 In the drawings, Figure 1 is a top plan view of a drag equipped with the improvement.

Fig. 2 is a view in end elevation of the same.

Fig. 3 is a sectional view taken on the line 55 3—3 in Fig. 1.

Fig. 4 is a top plan view illustrating a

modification whereby the cutting blade is tiltably supported.

Fig. 5 is an end view of said modified form.

Fig. 6 is a perspective view of the blade illustrated in Figs. 4 and 5, detached.

Corresponding parts in the several figures of the drawings are denoted by like characters of reference.

The drag as illustrated in the accompanying drawing comprises front and rear drag bars or runners, as they are sometimes known, said bars being designated by 15, 16, each of said bars being reinforced by a 70 plank 17 on the rearward face thereof. The drag bars are connected together and spaced apart by connecting bars 18 on which planks 19 constituting a platform are supported. Connecting bars 18 may be mortised into the 75 drag bars as shown and an additional obliquely disposed brace bar 20 may be used. The drag bars or runners are preferably obliquely disposed with respect to each other. The forward drag bar 15 is provided with a 80

wear plate 21 secured on the forward face adjacent to the lower edge thereof. The front drag bar is provided with a draft chain 22, suitably connected therewith and having a hitching link 23.

85 The blade or cutting member 24 consists of a bar or plate of steel of a length approximately equal to the length of the front drag bar or runner, said blade being preferably about four inches wide and three 90 eighths of an inch to half an inch in thickness, said blade being swaged to produce a cutting edge 25 at the forward edge thereof.

The cutting member 24 is supported with its bottom face approximately in the plane of 95 the bottom face of the drag bar 15 by means of brackets or arms 26, the construction being preferably reinforced by braces 27, if desired, the manner of supporting the blade being, however, largely optional. It is, how-

ever, important that the back 28 of the blade shall be properly spaced from the forward face of the front drag bar, producing an open space 29 the width of which may be from four to eight inches, more or less. 100

By the modified construction illustrated in Figs. 4, 5 and 6, the blade, here designated by 24' is tiltably supported in order that the cutting edge thereof may be lifted or raised upward to enable the blade to pass over obstructions which might be injurious to the cutting edge. By this construction the 110

brackets or arms here designated by 26' are provided with eyes 30 on the upper faces thereof, and the blade 24' is provided with lugs 31, riveted or otherwise secured to the 5 under face thereof and extending rearwardly for the passage of hinge bolts 32 whereby said lugs are connected with the eyes 30. The blade 24' itself is also concaved slightly in its upper face as shown at 33, and it will 10 be noted that when the blade is hingedly connected with the arms or brackets its position is only approximately horizontal. The operation thereof, however, will be very nearly identical with that of the horizontally 15 disposed blade illustrated in Figs. 1 to 3 inclusive, because it will cut beneath the surface of the dirt, and the dirt dislodged by the blade will fall behind the same and in advance of the forward drag bar 15 to be 20 crushed and compacted thereby.

The blade 24' is provided with upwardly extending arms 34 which are connected by rods 35 with a hand lever 36 suitably fulcrumed on the drag, said hand lever having 25 a stop member 37 engaging a rack segment 38 whereby the lever and the parts controlled thereby will be retained securely at various adjustments. By this hand lever the blade 24' may be tilted to the position 30 shown in dotted lines in Fig. 5, lifting the front edge thereof so as to enable it to ride over any obstructions that may present themselves.

In the operation of this device, the drag 35 is drawn over the ground in the customary manner. Rough and uneven high portions will be shorn from the surface of the road by the blade or cutting member 24 or 24', as the case may be, the cuttings passing over 40 the blade and being deposited in the space 29 in advance of the forward runner bar. By the action of the runner bars the cuttings will be crushed, distributed in the low spaces, and compacted, leaving the surface 45 of the road in an excellent condition.

When the conventional drag is used without the blade or cutting member of the present invention, the front runner bar is

entirely depended upon to remove the high portions by the scraping action of the bar. 50 When the soil is hard and dry, the drag is very liable to pass over the high places, and the results produced will hardly be perceptible. Even if portions of the high places are removed, the cuttings will be distributed and compacted in an inferior manner. By the application of the improved blade the cutting member or draft will be materially lightened, and the cuttings shorn by the blade will be deposited in a crumbled 55 and loose state in advance of the drag bars, the only function required of which will be to distribute, crush and compact the cuttings. It follows that a much superior result may be obtained in a more speedy and 60 less expensive manner and with a great saving of power.

Having thus described the invention, what is claimed as new is:

1. In a road drag, a ground engaging 70 crushing element, brackets connected with the front face of said element near the lower edge thereof and extending forwardly with respect thereto, and a substantially horizontal blade supported by said brackets in 75 spaced relation to the crushing element, said blade having its cutting edge approximately in the plane of the bottom face of the crushing element; said blade being adapted to shave or cut the high places in the ground, 80 the material cut by said blade being distributed in front of the crushing element.

2. A road drag having ground engaging front and rear crushing and leveling bars, 85 brackets connected with and extending forwardly with respect to the front crushing bar, eyes on said brackets, a cutting blade having rearwardly extending lugs, means for hingedly connecting the lugs with the eyes on the brackets, thereby sustaining the 90 blade tiltably and in an approximately horizontal position, and means whereby said blade may be tilted to swing the cutting edge thereof in an upward direction.

In testimony whereof I affix my signature. 95
JOHN DUDEK.
